FIG.1

FIG.2

FIG.3

FIG. 4

FIG. 5

FIG. 6

FIG. 1 is a perspective view of a postural drainage table embodying my new design as viewed from one side and above thereof with a tiltable table part in horizontal position;

FIG. 2 is a side elevational view thereof;

FIG. 3 is a top plan view thereof;

FIG. 4 is an elevational view of one end thereof;

FIG. 5 is an elevational view of the other end thereof; and

FIG. 6 is a perspective view thereof with the tiltable table part in tilted non-horizontal position.

The bottom of the tiltable table part is a conventional non-ornamental, open-work frame underlying the mattress-like pad.

I claim:

The ornamental design for a postural drainage table, substantially as shown and described.
